JOHN L. OSGOOD, OF BUFFALO, NEW YORK.

TOOL-HANDLE.

1,355,685.

Specification of Letters Patent.

Patented Oct. 12, 1920.

Application filed December 16, 1918. Serial No. 266,954.

To all whom it may concern:

Be it known that I, JOHN L. OSGOOD, a citizen of the United States, residing at Buffalo, in the county of Erie and State of New York, have invented a new and useful Improvement in Tool-Handles, of which the following is a specification.

This invention relates more particularly to wooden tool handles of the kind used for files and other hand tools having a slender tapering tang which is driven into an axial hole in one end of the handle for securing the handle on the tool. The handle is retained on the tool by friction and works loose in the use of the tool so that the tang has to be driven farther and farther into the handle from time to time to properly secure the tool, with the result that the handle is sooner or later split or destroyed unless it is suitably reinforced. The small inner end or neck of these handles is usually surrounded by a metal ferrule, but as a metal grip or metal surface on the portion of the handle which is grasped by hand is objectionable for various reasons, these ferrules are made short and small and they do not prevent the splitting of the handles. Various kinds of reinforcements have been proposed for such handles, but they either add materially to the cost of the handles or are objectionable for one or another reason.

The object of this invention is to produce a tool handle of the kind described which has the extended wood grip, the wood socket to receive the tang of the tool and other recognized advantages of the ordinary wood handle, but is provided with reinforcing means which, while effectually preventing the splitting of the handle and making it stronger and more durable, is so simple and inexpensive as not to add appreciably to the cost of production of the handle.

This is accomplished by pressing or driving into the body of the handle between the exterior surface thereof and the center of the handle containing the tang hole, a thin, metal ring or short tube which is left embedded in the handle at, or about the inner end of the tang hole and a considerable distance from the end of the handle.

In the accompanying drawings:

Figure 1 is an elevation partly in section, showing a tool handle embodying the invention.

Fig. 2 is an enlarged fragmentary section

showing the handle before the reinforcing ring is driven fully into place.

Fig. 3 is a similar section of the completed handle.

Fig. 4 is a transverse section thereof on line 4—4, Fig. 3.

A represents a handle for a file or other tool B, having a tang 10 adapted to be driven into an axial hole 11 in the end of the handle. Wood has certain recognized advantages for the handles of hand tools, and the handle is, therefore, preferably made of wood, but other suitable material could be employed. In this specification the word "wood" is intended to cover other suitable material analogous in characteristics to wood. The handle may be of the usual or any suitable shape, but it preferably has the usual short neck or reduced end portion surrounded and protected by a short metal ferrule 12, the inner end of which is preferably driven a short distance into the shoulder 13 of the handle to secure the ferrule in place.

14 represents a short, thin, metal tube or ring which is embedded in the handle at, or about the inner end of the tang hole, and extends longitudinally of the handle between the exterior thereof and the tang hole or longitudinal axis of the handle. The ring is much shorter than the tang hole and is located a considerable distance inwardly from the end of the handle, thus leaving a substantial portion of the tang hole unsurrounded by the ring. The ring being thin and having a relatively thin and sharp edge, can be readily pressed or driven into the handle by means of a press equipped with a suitable tubular punch, without first cutting or recessing the handle for the reception of the ring except to make a shallow annular starting recess in the end of the handle for guiding the ring. After the ring has been pressed into the handle the wood will expand again between the ring and the outer end of the handle so that the core 15 of wood which is located within the annular cut made by the ring and contains the tang hole will be confined and reinforced by the surrounding portion of the handle. Since the ring 14 is short and near the inner end only of the tang hole, a considerable portion of the core 15 of the handle between the ferrule 12 and the ring 14 is left unsurrounded by the metal.

While, therefore, the ring is adapted to prevent the splitting of the handle, the portion of the core not surrounded by the tube or ring is not rigidly confined and is adapted to expand more or less as the tang is driven into the hole, and the core 15 is not apt to be split by the wedging action of the tang. Furthermore, the tang of the tool is not apt to strike the short tube or ring at the 10 inner end of the tang hole and interfere with the firm seating of the tang in the handle because the extremity of the tang is slender, whereas the wider base or inner end of a wide tang might engage the outer end 15 of the ring or tube 14 if it extended to or near to the end of the handle.

I claim as my invention:

1. A tool handle formed of a single piece of slightly expansible material, and having 20 a tang hole in one end thereof to receive the tang of a tool, and a thin metal ring which is adapted to be forced into said handle between the exterior thereof and said tang hole, said ring being short and embedded in the handle adjacent the inner end 25 only of the tang hole and a substantial distance inwardly from the end of the handle, and leaving a central expansible core portion which contains said tang hole, and 30 which is free to expand as the tang is forced into said tang hole.

2. A tool handle formed of a single piece of slightly expansible material, and having

a tang hole in one end thereof to receive the tang of a tool, and a thin metal ring which 35 is adapted to be forced into said handle between the exterior thereof and said tang hole, said ring being materially shorter than the length of said tang hole and embedded in the handle adjacent the inner end of said tang hole, thereby leaving a central core 40 between said ring and the end of said handle which is free to expand as the tang is forced into said tang hole.

3. A tool handle having a tang hole in 45 one end thereof to receive the tang of a tool, a short ferrule surrounding the end of the handle adjacent the outer end only of said tang hole, and a thin metal ring which is adapted to be forced into said end 50 of the handle between the exterior thereof and said tang hole, said ring being short and embedded in the handle adjacent the inner end only of said tang hole and terminating a substantial distance from said ferrule, and leaving a central integral divided 55 core portion of the handle between said ring and said ferrule which is free to expand as the tang is forced into said tang hole.

Witness my hand this 14th day of December, 1918.

JOHN L. OSGOOD.
